UNITED STATES PATENT OFFICE.

MARTIN W. BRUESHABER, OF OAK PARK, ILLINOIS, ASSIGNOR TO THE GOSS PRINTING PRESS COMPANY, OF CHICAGO, ILLINOIS, A CORPORATION OF ILLINOIS.

FOLDER.

1,302,894.

Specification of Letters Patent.

Patented May 6, 1919.

Application filed April 9, 1917. Serial No. 160,826.

To all whom it may concern:

Be it known that I, MARTIN W. BRUESHABER, a citizen of the United States, and a resident of Oak Park, in the county of Cook and State of Illinois, have invented certain new and useful Improvements in Folders, of which the following is a specification, reference being had to the accompanying drawings.

10 This invention relates to folders of the type employing a cylinder for carrying a sheet or plurality of sheets past a pair of folding rollers, the cylinder being provided with a folding blade which is thrust outward as it passes the folding rollers for carrying the sheet or sheets into the bite of said rollers. In a folding machine of this type employing an internal gear meshing with a gear mounted upon the folding blade 15 shaft for the purpose of thrusting the blade outward into operative position between the folding rollers, a very considerable strain has been placed upon the mechanism, both by reason of the unbalanced condition at 20 the time the sheets are thrust outward into the bite of the folding rollers and also by reason of the considerable force which is required for projecting the folding blade in the desired manner. It is the principal 25 object of my invention to provide a form and arrangement of devices by which the folding mechanism as a whole shall be kept in as nearly as possible a balanced condition and by which the structure shall be strengthened and reinforced so as to prevent undue 30 strain upon the working parts. It is another object of my invention to improve folding machines in sundry details hereinafter pointed out. The preferred means by 35 which I have accomplished my several objects are illustrated in the drawings and are hereinafter specifically described. That which I believe to be new and desire to cover by this application is set forth in the claims.

40 45 In the drawings:

Figure 1 is a side view of one end of a folder embodying my improved construction;

Fig. 2 is an end view of the device shown in Fig. 1, as seen from the right in said figure;

Fig. 3 is an enlarged detail, being a vertical cross-section taken on line 3—3 of Fig. 2; and

55 Fig. 4 is a view similar to Fig. 2, but

showing a modified form of construction comprising two folding blades which are brought alternately into the bite of the folding rollers.

Referring to Figs. 1 to 3, in which corresponding parts are indicated by the same reference characters,—10 indicates a folding cylinder mounted upon and adapted to revolve with a shaft 11 which is mounted in any suitable bearings not shown. A folding blade 12 is fixedly mounted upon a shaft 13 which is revolubly mounted in the cylinder 10 longitudinally thereof in a suitable longitudinally-extending recess formed in the face of the cylinder. The shaft 13 has fixedly mounted upon its end portion beyond the end of the cylinder 10 a gear 14 which meshes with an internal gear 15 fixedly mounted in position. In the construction shown the gear 15 has a three-to-one relation to the gear 14, whereby the blade 12 is projected outward beyond the face of the cylinder 10 at three points circumferentially about the cylinder for each complete revolution of the cylinder. Folding rollers 16—17 are so positioned as to receive the edge of the blade 12 between them at one time for each rotation of the cylinder 10.

My improved means for balancing the folder and for reinforcing it comprise a heavy fly-wheel 18 preferably in the form of a disk, being fixedly mounted upon the shaft 11 and furnishing a bearing for the outer end of the shaft 13. The fly-wheel 18 is also provided with a weight 19 secured thereon diametrically opposite the shaft 13, such weight being adapted to balance the cylinder as a whole with reference to the weight of the folding blade and its co-acting parts.

The shaft 13 is further reinforced in my improved construction by means of rollers 20—21 revolubly mounted on said shaft at opposite sides of the gear 14, said rollers being adapted to engage rings 22—23, respectively, fixedly mounted on opposite sides of the internal gear 15. By this means the gear 14 is held in proper mesh with the gear 15 without having the outer ends of the teeth of either gear brought forcibly into contact with the other gear. The shaft is still further reinforced by means of arms 24—25 revolubly mounted upon the shaft 13 adjacent to the rollers 20—21, respectively, said arms being provided at their ends with roll-

ers 26 which run in suitable annular grooves in the outer faces of the rings 22-23. The arms 24-25 and the rollers 26 are held in position relative to the rings 22-23 by means of annular retainers 27-28 fixed upon the outer faces of the rings 22-23, respectively, and provided with flanges 29 extending inward opposite the rollers 26.

The construction shown in Fig. 4 is very similar to that shown in Figs. 1 to 3, and the corresponding parts are indicated by the same reference characters, but with the addition of an exponent a . In this construction a shaft 30 is provided in addition to the shaft 13 a , the shaft 30 being provided with a folding blade 31. The shaft 30 is also provided with a gear 32 which meshes with the gear 15 a , and is otherwise equipped in a manner similar to that described in connection with the shaft 13.

By reason of the provision of my improved balancing and reinforcing means, I am enabled to employ a folding blade shaft of moderate size which will stand up under the strain placed upon it in use, and the operation of the folder is rendered smoother and more even. So far as I am aware, I am the first in the art to provide a bearing for the outer end of the shaft and folding blade in a machine of this type, and my claims are to be construed accordingly. Moreover, it will be understood that I do not wish to be restricted to the use of my preferred form of construction in which the out-bearing member is in the form of a fly-wheel, except as hereinafter specifically claimed.

What I claim as my invention and desire to secure by Letters Patent, is—

40. 1. In a folder, the combination of a shaft, a cylinder fixedly mounted on said shaft so as to rotate therewith, a folding blade shaft revolvably mounted on said cylinder near its periphery, a folding blade mounted on said second-named shaft, an internal gear fixedly held in position adjacent to said cylinder, a gear fixed on said folding blade shaft beyond the end of the cylinder and meshing with said internal gear, and a bearing member fixedly mounted on said first-named shaft and providing a bearing for said second-named shaft beyond said second-named gear.

55. 2. In a folder, the combination of a shaft, a cylinder fixedly mounted on said shaft so as to rotate therewith, a folding blade shaft revolvably mounted on said cylinder near its periphery, a folding blade mounted on said second-named shaft, an internal gear fixedly held in position adjacent to said cylinder, a gear fixed on said folding blade shaft beyond the end of the cylinder and meshing with said internal gear, and a heavy fly-wheel mounted on said first-named shaft and providing a bearing for said second-named shaft beyond said second-named gear.

3. In a folder, the combination of a shaft, a cylinder fixedly mounted on said shaft so as to rotate therewith, a folding blade shaft revolvably mounted on said cylinder near its periphery, a folding blade mounted on said second-named shaft, an internal gear fixedly held in position adjacent to said cylinder, a gear fixed on said folding blade shaft beyond the end of the cylinder and meshing with said internal gear, and bearing means carried by said first-named shaft for the end of said folding blade shaft beyond said second-named gear, said bearing means being weighted on the side thereof diametrically opposite said folding blade for balancing the cylinder as a whole with reference to the folding blade and its attached parts.

4. In a folder, the combination of a shaft, a cylinder fixedly mounted on said shaft so as to rotate therewith, a folding blade shaft revolvably mounted on said cylinder near its periphery, a folding blade mounted on said second-named shaft, an internal gear fixedly held in position adjacent to said cylinder, a gear fixed on said folding blade shaft beyond the end of the cylinder and meshing with said internal gear, a stationary ring of a greater diameter than said cylinder secured in position opposite the end of said cylinder, and radially-extending means slidably connected at its outer end portion with said ring and revolvably connected at its inner end portion with said second-named shaft for supporting the outer end of said shaft.

5. In a folder, the combination of a shaft, a cylinder fixedly mounted on said shaft so as to rotate therewith, a folding blade shaft revolvably mounted on said cylinder near its periphery, a folding blade mounted on said second-named shaft, an internal gear fixedly held in position adjacent to said cylinder, a gear fixed on said folding blade shaft beyond the end of the cylinder and meshing with said internal gear, a stationary ring placed radially outside of the path of said folding blade shaft and secured in position opposite the end of said cylinder, and an arm revolvably mounted on said second-named shaft and extending outwardly toward said ring, having a shifting bearing on said ring for supporting the outer end of said shaft.

6. In a folder, the combination of a shaft, a cylinder fixedly mounted on said shaft so as to rotate therewith, a folding blade shaft revolvably mounted on said cylinder near its periphery, a folding blade mounted on said second-named shaft, an internal gear fixedly held in position adjacent to said cylinder, a gear fixed on said folding blade shaft beyond the end of the cylinder and meshing with said internal gear, a stationary ring secured in position opposite the end of said cylinder and provided with an annular groove in its face, an arm revolvably mounted on said second-named shaft, and a roller revolvably

mounted on said arm adapted to run in the groove in said ring for supporting the outer end of said second-named shaft.

7. In a folder, the combination of a shaft, 5 a cylinder fixedly mounted on said shaft so as to rotate therewith, a folding blade shaft revolvably mounted on said cylinder near its periphery, a folding blade carried by said second-named shaft, an internal gear fixedly 10 held in position adjacent one end of said cylinder, a gear fixed on said folding blade
- shaft beyond the end of the cylinder and meshing with said internal gear, a stationary track member secured opposite the end of said cylinder and having a groove in one of its side faces, an arm revolvably mounted on said second-named shaft, a roller revolvably mounted on said arm and running in said groove, and another roller revolvably mounted on said second-named shaft and bearing 20 against the inner edge of said track member.

MARTIN W. BRUESHABER.
